DUDLEY F. STEVENS, OF BOSTON, MASSACHUSETTS.

Design No. 3,048, dated May 12, 1868.

DESIGN FOR A TRADE-MARK.

The Schedule referred to in these Letters Patent and making part of the same.

TO ALL PERSONS TO WHOM THESE PRESENTS SHALL COME:

Be it known that I, DUDLEY F. STEVENS, of Boston, of the county of Suffolk, and State of Massachusetts, have invented or produced a new and ornamental Design for a Trade-Mark; and do hereby declare the same to be fully described in the following specification, and represented in the accompanying drawing.

It consists of the delineation, a, of a lamp-chimney, cone, or case, and an ellipse or oval, b, encompassing such delineation, the whole being as represented.

I claim as my invention or production—

The design for a trade-mark, as described and shown.
